UNITED STATES PATENT OFFICE.

CHARLES R. TOST, OF CENTERDALE, RHODE ISLAND, ASSIGNOR TO THE HADLEY COMPANY, OF PROVIDENCE, RHODE ISLAND, A CORPORATION OF RHODE ISLAND.

BRACELET.

Application filed June 9, 1927. Serial No. 197,657.

This invention relates to bracelets which are used either as ornaments merely or as holders for wrist watches or other articles and has for its object the facile application and removal of the bracelet as well as security, durability, and attractive appearance. The invention is particularly applicable to bracelets of the link type, either extensible or non-extensible.

- 10 Referring to the accompanying drawings: Fig. 1 is a plan view;
 Fig. 2 is a side elevation;
 Fig. 3 is an enlarged side elevation with the cover open;
 15 Fig. 4 is an enlarged view similar to Fig. 1 showing parts broken away;
 Fig. 5 is a section on line 5—5 of Fig. 2; and
 Fig. 6 is a perspective view of one of the 20 links.

In the drawings the invention is illustrated as applied to a bracelet having extensible links comprising inner and outer parts 1 and 2 telescoping together endwise of the 25 bracelet with an interior spring normally to hold the parts together as shown at the left-hand side of Figs. 1 and 2. Inasmuch as this type of link is very common, it is not illustrated in detail. It will, of course, be understood that the invention is equally applicable to bracelets in which the links are non-extensible.

As shown in Figs. 3 and 4 the male and 35 female links 3 and 4 are interconnected by a tongue and groove connection extending transversely of the bracelet. The tongue 5 is in the form of a roll or bead joined to the inner part of the link 4 by a neck 6 of reduced dimension normal to the bracelet. The 40 link 3 is formed of pressed metal in a box-like shape with the longitudinal edges meeting at 7 (Figs. 4 and 6). At one end the link 3 has perforated ears to receive pin 9 for pivoting the link to the next adjacent 45 link 10. At the other end the link 3 is provided with an opening 11 extending across the link and through one side (the upper side in Fig. 6) of the link to form a groove

for receiving the tongue 5 telescopically from the side. The other side of the link 50 is preferably closed as shown at 12 in Fig. 6 to constitute a stop for the tongue or connector 5. The end of the link 3 is provided with a slot 13 to receive the neck 6 of the connector 5.

For the purpose of holding the connector 5 in the opening 11 a cover 14 is pivoted on the pin 9 with a side flange 15 which closes the open end of the opening 11 as shown in Figs. 1, 2 and 4. For the purpose of holding the cover 14 in closed position it may be provided with an indentation 16 which snaps into a groove 17 in the link 3 when the cover is closed. A spring 18 may also be provided in the link 3 frictionally to engage 65 the connector 5 at 19 so that the connector will not accidentally drop out of the opening when the cover 14 is raised preparatory to opening the bracelet.

From the foregoing it will be evident that 70 the bracelet may be opened by merely raising the cover 14 and sliding the connector (downwardly in Fig. 4) out of the opening 11, the spring 18 preventing the connector from slipping out accidentally while the 75 cover 14 is being raised. By this invention the connector 5 may comprise the usual roll ordinarily provided to receive a pivot pin (such as 9) to join adjacent links.

I claim:

1. A bracelet comprising male and female links having tongue and groove parts telescoping together along a line extending crosswise of the bracelet, and a spring pressing said parts against each other transversely of said line for frictionally maintaining the links in interengagement.

2. A bracelet comprising a link having a connector extending across one end with a neck of reduced dimension normal to the 90 bracelet, a link having an opening extending across one end and through one side to receive said connector telescopically from the side and a slot of reduced dimension in the end of the latter link to receive said neck, 95 and a spring pressing the telescoping parts

together transversely of the direction of telescopic movement frictionally to hold said connector in said opening.

3. A hollow bracelet link having an opening extending across one end and through one side to receive a connector telescopically from the side, and a leaf spring in the link for frictionally engaging the connector, the

spring extending along one side of the link, thence along the end and thence along the other side, with its end bent into approximate parallelism with the telescopic path of the connector.

Signed by me at Providence, Rhode Island, this 7th day of June, 1927.

CHARLES R. TOST.
